UNITED STATES PATENT OFFICE.

JAMES N. HEALD, OF WORCESTER, MASSACHUSETTS, ASSIGNOR TO THE HEALD MACHINE COMPANY, OF WORCESTER, MASSACHUSETTS, A CORPORATION OF MASSACHUSETTS.

WATER TANK FOR GRINDING MACHINES.

Application filed September 15, 1922. Serial No. 588,514.

To all whom it may concern:

Be it known that I, JAMES N. HEALD, a citizen of the United States, residing at Worcester, in the county of Worcester and 5 Commonwealth of Massachusetts, have invented a new and useful Improvement in a Water Tank for Grinding Machines, of which the following, together with the accompanying drawings, is a specification.

10 The present invention relates to grinding machines, and in particular to the provision with such a machine of means for conveniently securing the supply, discharge and replenishment of the water that is used in the 15 operation of grinding.

The several features of the invention are set forth in full hereinafter, reference being had to the accompanying drawings wherein,—

20 Fig. 1 is a plan view of the improvement shown in relation to so much of a grinding machine as is necessary to disclose the operation thereof.

Fig. 2 is an end view of the parts shown 25 in Fig. 1.

Fig. 3 is a side view of the improved tank with a portion of its wall cut away to disclose the interior construction.

Like reference characters refer to like 30 parts in the different figures.

It is the general practice in wet grinding operations to provide the water supply for the machine by the use of a tank, which is connected suitably with the water circulating system, in such a manner that water is drawn or pumped from one end of said tank, and subsequently discharged or drained back into the other end. In many machines the water tank is made integral 35 with the base of the machine, but in order to facilitate cleaning and replenishment of the water supply, it is of great advantage to make the tank removable from the machine.

40 45 It has heretofore been proposed to mount such a removable tank on wheels or rollers, and to provide, in conjunction with this mounting, for the dumping or tipping of the tank body, the latter involving of necessity, the provision of more or less complicated locking devices, not only for holding the body in normal untipped position, but also for holding the entire structure in proper position relative to the machine and to the pump driving devices thereof, to pre-

vent any displacement by the shifting of its roller or wheel supports.

The present invention aims to simplify and to render less expensive the provision of such a tank, by doing away with the necessity for rollers or wheels thereon and the necessity for dumping and locking instrumentalities,—without however, detracting in the least from the portability of the structure. As shown in the drawings, the 60 grinding machine provides the usual water circulating system 1, which in the case of the plain grinder here illustrated, consists essentially of a flexible supply conduit carried by the wheel slide 2, and terminating 65 at 3 adjacent to the grinding wheel 4. The water is drawn or forced into the conduit 1 by a suitable pump 1^a, driven by a belt 1^b and preferably located in a tank compartment 5; the discharge of water from the 70 wheel 4 is into the usual pan 6 of the machine, the latter having an outlet 7 to direct the water into another tank compartment 8.

The two compartments 5 and 8 are formed 80 in a single tank structure consisting of side walls 9, 9, bottom 10, front wall 11, and sloping rear wall 12; the movable baffle plate or partition 13, suspended from the side walls 9, 9 by pivot studs 14 separates the two compartments 5 and 8. The baffle plate or partition 13 normally bears against suitable flanges 15, 15 provided by the side walls 9, but is equipped with a handle 16 which enables it to be swung backwardly on its pivot 85 studs to give access to the compartment 5 for the purpose of cleaning out any sediment that has been carried over into said compartment 5 from the compartment 8.

The tank structure thus constructed has its 90 bottom 10 supported at the four corners thereof upon legs 17, 17, the lower ends or feet of which are adapted to rest upon the floor, as shown,—the proportion of parts being such that when the tank structure is thus 100 operatively positioned relative to the grinding machine, there is considerable clearance space, as indicated at 18, between the top of the tank and the underside of the machine pan 6. The spacing between the legs 17, 17 is such as to permit the passage between them, either sidewise or endwise of the tank, of an ordinary type, such as the Cowan type, of shop conveyor, as illustrated 105 at 19, Figs 1 and 2, and the height at which 110

the tank bottom 10 is held above the floor by said legs 17, 17, is such as to admit freely the lowered platform or support 20 of said conveyor, while at the same time being engageable by said platform when the latter is raised by depression of the handle bar 21 of the conveyor. In other words, the dimensions and proportions adopted for the legs and bottom of the tank structure are the same substantially, as regards spacing and elevation from the floor, as the corresponding dimensions and proportions of the usual merchandise-supporting skids or platforms that are used in conjunction with conveyors of the above described type.

In consequence of this arrangement, the standard conveyor of the Cowan, or any other well known type, forming a part of the regular shop equipment, can be readily disposed, in its lowered position, directly beneath the bottom 10 of the tank and between the legs 17, 17 on either side or end. The elevation of the conveyor's platform 20 serves to elevate the entire tank structure above the floor, in precisely the same way as the conveyor is used to elevate one of the loaded skids that is furnished as part of the conveyor equipment. When thus supported on the conveyor rather than on the floor, the tank structure can be wheeled about at will on the rollers 22 of the conveyor, and moved to a convenient place for dumping, cleaning and refilling; thereafter the conveyor serves for wheeling the tank back in position beneath the pan 6 of the machine, and for lowering it on to the floor, allowing the legs 17 to support it in a stationary position, without the need for any locking devices whatsoever.

The sloping outer end 12 of the tank is formed with a curved lip 23 which facilitates the removal, when desired, from the compartment 8 of the sediment and wheel dust

that collects in said compartment during the operation of grinding, and that is prevented from passing into the compartment 5 in any great quantity, due to the interposition of the baffle plate 13. The pitcher lip 23 and the sloping end 12 permit this material to be scraped or scooped out of the tank, without interruption to the operation of grinding or to the circulation of water through the tank and through the pipe 1. For the removal of any sediment or wheel dust that finds its way into compartment 5, the baffle plate 13 may be swung back to give access to said compartment 5.

I claim,

1. A portable water supply tank for a grinding machine, said tank having three vertical walls and one sloping wall, all of them rectangular, a pivotally mounted baffle plate, dividing the tank, being adapted to swing towards the sloping wall and with it forming a settling compartment, a pump in the other compartment, and legs under the tank spaced and of such a height as to receive and permit the tank to be lifted by a wheeled conveyor of the lifting type.

2. A portable water supply tank for a grinding machine, said tank having three vertical walls and one sloping wall, all of them rectangular, a pivotally mounted baffle plate dividing the tank, being adapted to swing toward the sloping wall and being normally held in a vertical position by water pressure and by flanges on two parallel vertical walls and dividing the tank into a settling compartment and a pumping compartment, the settling compartment including the sloping wall, and legs under the tank spaced and of such a height as to receive and to permit the tank to be lifted by a wheeled conveyor of the lifting type.

Dated this 13th day of September 1922.
JAMES N. HEALD.
